CLAIM

The ornamental design for a solar powered garden light, as shown and described.

DESCRIPTION

1. Solar powered garden light

1.1 : Perspective

1.2 : Perspective

1.3 : Front

1.4 : Back

1.5 : Left

1.6 : Right

1.7 : Top

1.8 : Bottom

1.9 : Enlarged

The parts shown by means of broken lines in the reproductions are not part of the claimed design; fig. 1.9 is an enlarged view of the portion taken at line 9 in fig. 1.2; the dash-dot-dash lines in figs. 1.2 and 1.9, and the label "9" in fig. 1.2 are for the purpose of depicting the cut line of the enlarged view and form no part of the claimed design.
